SHOE POSITIONING AND CLAMPING MEANS

Thomas Baggott Clarke and William Arthur Barker, Leicester, England, assignors to United Shoe Machinery Corporation, Flemington, N. J., a corporation of New Jersey

Application July 2, 1946, Serial No. 680,970
In Great Britain August 14, 1945

11 Claims. (Cl. 1—32)

1

This invention relates to improvements in heel attaching machines and is illustrated herein as embodied in a heel positioning and clamping device which may be advantageously used in the above or other machines for operating upon the heel ends of shoes.

Preparatory to attaching heels by outside nailing to shoes mounted upon lasts it is common practice to position, in register, a heel upon a nailing block and a shoe mounted upon a jack post, the jack post thereafter being moved toward the heel block and/or the heel block being moved toward the jack post to cause the heel and the shoe to be forced against each other with considerable pressure. The heel ends of shoes are commonly positioned in heel attaching machines by crease plates or finders. It has been found, however, that whenever such plates are relied upon to prevent lateral tilting movement of the last, and accordingly the shoe, upon the jack post spindle during the heel nailing operation, there is a tendency for the crease plates to be forced too far into the rand crease of the shoe.

It is an object of the present invention to provide an improved device for quickly and effectively positioning and clamping shoes in heel attaching machines.

With the above object in view there is provided, in accordance with a feature of the present invention, in combination with crease plates for positioning the heel end of a shoe in a machine, clamps or blocks yieldingly movable with equalized primary pressure against opposite sides of the counter portion of the shoe in response to positioning movement of the shoe, and yieldable power operated mechanism for applying equalized secondary pressure against the blocks. In the use of the illustrative device the shoe, positioned heightwise by crease plates mounted for equal and opposite movement laterally of the shoe, is moved rearward against a fixed back gage or stop, a yieldable crease plate which cooperates with the above mentioned crease plates in positioning the shoe heightwise entering the rand crease at the rear end of the shoe before the shoe engages the back gage. The rear end of the counter portion of the shoe during its positioning movement engages and moves rearward with it a forked slide which is operatively connected, through suitable yieldable pressure equalizing mechanism, to the blocks causing said blocks to be forced with primary pressure against opposite sides of the shoe counter. The blocks are frictionally held against movement upon carriers therefor but are permitted to slide, to a limited extent, lengthwise of the

2

shoe being positioned, said blocks also being permitted to rock simultaneously about shifting axes extending generally heightwise and lengthwise respectively of said shoe, the construction and arrangement being such that the blocks orient themselves to the contour of the shoe counter as the shoe is positioned in the device. After positioning the shoe and initially clamping it as above described, yieldable mechanism operated by power of the machine and constructed and arranged to apply equalized force against the blocks forces said blocks with secondary pressure against the shoe counter to hold the shoe against lateral tilting moving during the heel nailing operation.

15 The above and various other features of the invention will be understood and appreciated from the following detailed description read in connection with the accompanying drawings in which

Fig. 1 is a perspective view, partly broken away and partly in section, of the illustrative positioning and clamping device;

20 Fig. 2 is a plan view, partly broken away and partly in section on line II—II of Fig. 1, of the device;

25 Fig. 3 is a vertical section of the illustrative device on line III—III of Fig. 1 and shows portions of nail inserting mechanism and a shoe which is positioned in the machine ready to have its heel attached;

30 Fig. 4 is an enlarged plan view, partly broken away, of one of a pair of crease plates of the machine and supporting mechanism therefor;

Fig. 5 shows in perspective one of a pair of shoe clamps of the device;

35 Fig. 6 is a section on line VI—VI of Fig. 3 showing in plan mechanism through which the clamps are forced with secondary pressure against the shoe;

Fig. 7 is a plan view of a slidable fork for centralizing the rear end of the shoe in the machine;

40 Fig. 8 and 9 are vertical and horizontal sections of the clamps on line VIII—VIII of Fig. 2 and on line IX—IX of Fig. 5 respectively;

Fig. 10 is a plan view showing portions of mechanism for causing inward movement of the clamps in response to rearward movement of the fork shown in Fig. 7;

Fig. 11 is a section on line XI—XI of Fig. 10; and

50 Fig. 12 shows in side elevation a portion of the machine for operating the clamps by power.

The illustrative shoe positioning and clamping device, which may be used advantageously in various types of heel attaching machines or in other machines for operating upon the heel ends

of shoes, will be described with reference to the machine disclosed in United States Letters Patent No. 2,259,568, granted on October 21, 1941, on an application filed in the names of Thomas A. Kestell et al. In that machine, as in the present machine a shoe 20 (Fig. 3), mounted upon a last 22, is placed upon a last spindle 24 of a jack post 26 which is swung rearward from its dash line, unloading position (Fig. 3) to its substantially vertical, full line, operative position. When the shoe 20 has been positioned in the device, by mechanism which will be hereinafter described, the jack post 26, together with the shoe 20, is moved vertically toward a heel 28, positioned upon a nail block 30, with the result that the heel-seat portion 32 of the shoe is forced with considerable pressure against the cup or attaching face 34 of the heel. Thereafter, nails 36, positioned in passages 38 of the nail block 30, are driven by drivers 40 through the heel 28 and the heel-seat portion 32 of the shoe, the point ends of the nails being clenched by a steel heel plate 42 of the last.

It is desirable that a rand crease 44 of the shoe 20 being positioned in the machine and moved toward the nail block 30 shall be parallel to the rim of the cup 34 of the heel on the nail block 30, and, accordingly, the illustrative device comprises crease plates or finders 46 (Figs. 1, 2, 3, and 4), 48 (Figs. 1, 2, 3, and 7), which engage in the rand crease 44 at opposite sides and the rear end of the shoe, respectively, as the shoe is presented to the device. The crease plates 46, in combination with a bifurcated slide or fork 50, which is yieldingly movable rearward under pressure of the shoe, serve to position the shoe widthwise as it is moved rearward into engagement with a fixed back gage or stop 52 forming part of a carrier block 54. The slide 50 and the crease plates 46 may be described as constituting a centralizing gage. As will be explained later, the bifurcated slide 50 is yieldingly connected to a pair of clamps 56 which, as the shoe is being positioned in the machine, swing in from opposite sides of the shoe 20 under pressure of the shoe against the slide, said clamps orienting themselves into proper relation with the shoe, and, upon actuation of a treadle (not shown) of the machine, being forced under powerful spring pressure against the shoe to insure against the shoe tilting or rocking laterally upon the spindle 24 of the jack post 26.

The crease plates 46, as will be explained later, are initially set to engage in the rand crease 44 of the shoe, and are moved apart against spring pressure by said rand crease as the shoe is moved rearward. Each of the crease plates 46 is mounted upon a pivot pin 58 (Figs. 1, 2 and 4) threaded into a holder 60 having a slot 62 of suitable shape to receive the forward end of an elongated arm or carrier 64 (Figs. 1 to 4 and 10) 64a (Figs. 1, 2, and 10), the holders 60 being initially set in different adjusted positions upon their associated arms by screws 66 threaded into the holders, the settings of the holders upon the arms being such that when the shoe 20 is positioned in the device, the crease plates 46 will engage in portions of the rand crease in the vicinity of the heel-breast line of the shoe. The arms 64, 64a together with their associated holders 60 may be defined as carriers for the crease plates 46. Each of the crease plates 46 is normally forced against a shoulder 68 (Fig. 4) of its associated holder 60 by a spring 70, opposite ends of which are housed in recesses of the holder and the crease plate, the construction and arrangement being such that the crease plates can, within limits, swing about their pins 58, the

axes of which may be said to extend heightwise of the shoe and to be arranged adjacent to shoe-engaging portions of the plates, in order effectively to follow in the rand crease 44 of the shoe as the shoe is positioned in the device. The arm 64a is formed integral with a vertical stem 72 (Figs. 1, 2 and 3) and the arm 64 is formed integral with a sleeve 74 (Fig. 3) which is arranged in concentric relation with said stem and is rotatable in a bore 76 of a transversely adjustable slide 78 (Figs. 1 and 3). The sleeve 74 is mounted for rotation in the slide 78, a collar 80, secured to the sleeve, being in engagement with the upper surface of the slide, and a lip 82 (Fig. 3) of the sleeve being in engagement with the lower face of the slide 78. Mounted for rotation upon the sleeve 74, between the collar 80 and a collar 84 which is pinned to the upper end of the stem 72 and engages the top face of the sleeve, is a boss 86 of a lever 88 corresponding to lever 55 disclosed in said Letters Patent No. 2,259,568. The slide 78 is mounted in a transversely extending T-shaped guideway 90 of a supporting member 92 which is provided with a forwardly and rearwardly extending dovetail guideway 94 (Fig. 1) in which fits a dovetail shelf 96 (Figs. 1 and 3) formed integral with a slidable bracket 98 (Figs. 2 and 3) vertically movable upon a fixture 100, ball bearings 102 (Fig. 2) being interposed between the fixture and the bracket. The supporting member 92 is formed in part by a plate 91 (Figs. 1 and 3) which is recessed at its central portions and is secured to the main body of said member by screws 93. In the illustrative construction the slidable bracket 98 may be raised or lowered to provide clearance for the presentation of the heel 28 and nail delivering mechanism (not shown) to the machine and to facilitate the positioning of the shoe 20 in the device.

Suitable mechanism, not described herein but disclosed in said Letters Patent No. 2,259,568, is provided for initially setting the supporting member 92 in its proper, adjusted position on the shelf 96 and for clamping it in said position to the shelf. Extending rearward from the boss 86 of the lever 88 is an arm 103 (Figs. 1 and 3) pivotally connected to one end of a link 104, the other end of which is fulcrumed upon a stud 106 (Fig. 1) secured to the supporting member 92. Rotation of the lever 88 upon the sleeve 74 will cause transverse movement of the slide 78 in the guideway 90 of the supporting member 92. The slide 78 may be held against movement in the guideway 90 of the supporting member 92 by a pair of screws 108 (Fig. 1) threaded into the lever 88 and forced against abutments 110 (only one shown) formed integral with the supporting member 92. It will also be noted that, if desirable, lateral shifting of the slide 78 to accommodate right and left shoes may be permitted if the screws 108 are so adjusted that the lever 88 can be rotated within limits determined by said screws. The mechanism described in this paragraph is substantially identical with mechanism disclosed in said Letters Patent 2,259,568, which may be referred to for a description of the construction and operation of the machine as a whole.

Secured by screws 112 (Figs. 1 and 3) to the slide 78 is the above-mentioned carrier block 54 (Figs. 1, 2, 3 and 7) and a bracket 114 (Figs. 1, 2 and 3) having at its right end a boss 116 (Fig. 1) bored to receive a pin 118 (Figs. 1 and 2) upon which a multi-arm lever 120 is pivoted. Swiveled in the lever 120 is a pin 122 carrying a guide 124 provided with a bore through which passes an elongated rod 126 having its inner end

threaded into a block 128 pivotally mounted upon a pin 130 carried by the slide 13. Fixed to the rod 126 is a collar 132 (Fig. 2) which is held against the guide 124 by a spring 134 (Figs. 1 and 2), opposite ends of which engage the guide and a knurled head 136 of the rod. Pivotally connected to an inwardly extending arm 138 (Fig. 2) of the lever 120 is a link 140, the forward end of which is pivotally connected to the arm 64a.

It will be noted that the arms 64, 64a comprise several parts, forward portions 142, 142a (Figs. 1 and 2) of the arms being initially set in adjusted relation to two plate rear portions 144 (Figs. 1, 2, 3, 4 and 10), 144a (Figs. 1, 2 and 10) of said arms, the upper plates of said rear portions being formed integral with the sleeve 74 and stem 72 respectively. The crease plates together with their supporting mechanism may be referred to as crease plate or finder assemblies. When the rod 126 is adjusted by screwing it into and out of the block 128, the lever 120 is swung, by the action of the spring 134, about the pin 118, with the result that the arm 64a is adjusted toward or away from a central plane 146 (Figs. 1, 2 and 10) of the device. In order to cause movement of the arm 64a with relation to the central plane 146 to effect equal and opposite movement of the arm 64 with relation to said plane, there is provided a rod 158 (Figs. 1, 2 and 3), opposite ends of which are pivoted to the lever 120 and to the rear end of a T-shaped lever 150 (Figs. 1 and 2) fulcrumed upon a pin 152 carried by the left end of the bracket 114. Also pivotally connected to the T-shaped lever 150 is a link 154, the forward end of which is pivotally connected to a lug 156 secured by screws 158 (Fig. 2) to the rear part 144 of the arm 64. When the threaded rod 126 is rotated, the arms 64, 64a move equal distances in opposite directions with relation to the central plane 146.

The clamps 56, which are forced against the counter portion of the shoe 20 mounted upon the last 22 to hold it against tilting laterally on the last plate spindle 24 during the heel nailing operation, are indirectly mounted upon a pair of arms 160 (Figs. 1 and 2) secured to rocker pins 162 (Figs. 2, 3 and 10), 162a (Figs. 2 and 10), carried by the upper plates of the rear portions 144, 144a of the arms 62, 62a respectively. Each of the clamps 56 comprises a felt pad 164 secured to and forming part of a block 166 provided with a cylindrical passage 168 (Figs. 8 and 9) which has a radius of curvature 169 and which has an opening 170 (Figs. 5 and 8) at one of its sides. Engaging in the cylindrical passage 168 is a barrel-shaped portion or support 172 (Figs. 8 and 9) of a bracket 174 (Figs. 1, 2, 5, 8 and 9) to which is secured a vertically disposed threaded stud 176 extending through an elongated slot 178 (Figs. 1, 2 and 5) of a corresponding arm 160 and held secured to such arm by a thumb nut 180, the arm having in its bottom face a slot 182 (Figs. 1 and 5) in which a rib 184 (Figs. 8 and 9) of the bracket engages to insure against turning of the bracket on the arm. The maximum radius of curvature 185 of the barrel-shaped support or portion 172 which is curved in longitudinal section is substantially the same as the radius of curvature 169 of the cylindrical passage 168, the construction and arrangement being such that the block 166 slidingly fits on said support.

Rigidly secured to the bracket 174 by a screw 186 is a washer 188, which engages the forward face of the block 166, and yieldingly forced

against the rear face of the block is a washer 190 which is backed up by a spring 192 (Figs. 2, 3 and 9) held in operative position upon the bracket by a screw 194 threaded into said bracket. With the above construction the block 166 is frictionally held against movement with relation to the bracket 174, but is permitted to slide to a limited extent lengthwise of the shoe being positioned and also to rock simultaneously about shifting axes extending generally heightwise and lengthwise in order properly to orient itself to the counter portion of the shoe with which it engages. The blocks together with mechanism upon which they are supported may be referred to as clamping assemblies.

Secured by screws 196 (Figs. 1 and 2) to each of the arms 160 is a ratchet plate 198 having teeth 200 constructed and arranged to be engaged by a tooth 202 (Fig. 2) of a pawl 204 which is pivoted upon links 206 fulcrumed upon a pin 208 (Fig. 1) carried by a corresponding arm 64, 64a. A tension spring 210, front and rear ends of which are connected to studs respectively secured to the pawl 204 and to the corresponding arm 64, 64a, constantly urges the tooth 202 of the pawl 204 toward the ratchet teeth 200. Each of the pawls 204 has a rounded outer end arranged to be engaged by a hook-shaped forward end 212 (Figs. 1 and 2) of a bar 214 which is pivotally connected at its rear end to a lever 216 (Figs. 2, 3 and 6) fulcrumed upon a corresponding rocker pin 162, 162a, each of the bars being constantly urged rearward by a spring 218 (Fig. 2), opposite ends of which are fixed to studs respectively carried by the bar and the corresponding arm 64, 64a.

Each of the bars 214 has a wedge portion 220 (Figs. 1 and 2) opposite sides of which are arranged to engage respectively the outer end of the pawl 204 and a roll 222 which is rotatably mounted upon the fulcrum pin 118 or the fulcrum pin 152. As the bars 214 are moved forward, against the action of the springs 218, by mechanism which will hereinafter be described, the hook-shaped forward end 212 of each of the bars moves away from the outer end of the associated pawl 204 with the result that the tooth 202 of the pawl is moved by its spring 210 into engagement with one of the ratchet teeth 200. Continued forward movement of the bars 214 causes the pawls 204 to be deflected inward by the bars 214 acted upon by the rolls 222, to force the arms 160 inward, thereby forcing the blocks 166 against opposite sides of the counter portion of the shoe.

Secured to the lower end of each of the rocker pins 162, 162a is a lug 224 (Figs. 2, 3, 10 and 11) to which is pivotally connected the forward end of a rod 226 having a threaded outer surface 228 (Fig. 11) on which is screwed a forward portion of a coil spring 230. The rear portion of each of the springs 230 is screwed onto a threaded outer surface of a rod 232, which is pivotally connected to a rocker 234 fulcrumed on a stud 236 secured to the rear end of the bifurcated slide 50 which is mounted for forward and rearward movement on the block 54 and is constantly urged forward to its idle position shown in Fig. 10 by tension springs 238 having their forward and rearward ends fixed to a rod 240 secured to the block and to a bar 242 secured to the rear end of the slide.

The levers 216 are provided with faces 244 (Fig. 6) constructed and arranged to be engaged by vertically offset projections of an equalizer bar 246 (Figs. 3 and 6) slidably mounted on a

flat upper surface of the carrier block 54 and pivotally connected at its center to the forward end of a link 248, the rear end of which is pivotally connected to a lower arm 250 (Figs. 2, 3 and 6) of an offset bell-crank lever 252, (Figs. 2 and 6) fulcrumed upon a pin 254, secured to the supporting member 92. An upper arm 256 of the bell-crank lever 252 is pivotally connected to a block 258 which has a bore for receiving, and is adjustably secured to, a transversely extending rod 260 (Figs. 2, 3 and 6). The rod also passes through a bore in, and is adjustably secured to, a block 262 pivotally connected through a pin 264, secured to the block, with an upper arm 266 of an offset bell-crank lever 268, secured to a fulcrum pin 270, rotatably mounted in the vertically slidable bracket 98. The fulcrum pin 270 also has secured to it a lower arm 272 which is operatively connected to the forward end of a rod 274 pivotally connected at its rear end to a bell-crank lever (not shown), corresponding to the bell-crank lever 157 disclosed in said Letters Patent, the rod being moved rearward by a powerful spring 251 (Fig. 12), upon operating a treadle 253, to cause the clamps 56 to be forced with considerable secondary pressure against the shoe 20. When the powerful spring 251 which operates the rod 274 is compressed at the end of the heel-nailing operation, the rod is moved forward, causing, through the mechanism above described, the tooth 202 of each of the pawls 204 to swing away from the teeth 200 of an associated ratchet plate 198. The treadle 253 is operatively connected to a latch plate 255 to free upon depression of said treadle, a bell crank lever 257 for counterclockwise movement as viewed in Fig. 12 under the action of a spring 251, thereby moving the rod 274 rearward and accordingly independently forcing the clamps 56 with substantial yielding pressure against the counter portion of the shoe. Continued depression of the treadle 253 is effective to trip a one-revolution clutch 259 to cause the machine to move through its first power cycle. Near the end of a second power cycle of the machine during which a top lift is attached to the heel, a cam actuated clutch throw-out lever 261 actuates latch mechanism 263 which cooperates with other mechanism disclosed in detail in the Kestell et al. Patent 2,259,568 to render effective the latch plate 255 causing re-compression of the spring 251 and the opening of the clamps 56.

As a shoe 20, positioned heightwise, as above explained, by the crease plates 46, is moved rearward, it engages the bifurcated slide 50. As the slide 50 acted upon by the shoe moves rearward, it moves with it the rocker 234 and through the coil springs 230, the front and rear ends of which are secured to rods 226 and 232 respectively pivoted to the lugs 224 of the pins 162, 162a and to the rocker 234, swings the arms 160 which are secured to the pins inward until the blocks 166 are forced with primary pressure against the opposite sides of the counter portion of the shoe. Continued rearward movement of the shoe 20 and the bifurcated slide 50 causes the clamps 56 to be forced with yielding equalized pressure against the shoe, the blocks shifting upon the barrel-shaped portions 172 of the brackets 174 in the manner above described, under the action of the shoe, to orient themselves to the shoe. At approximately the same time that the shoe engages the bifurcated slide 50 the rear end of its rand crease 44 engages the rear crease plate 48 which is mounted for sliding movement against the

action of a spring 280 (Fig. 3) in a guideway 216 of the carrier block 54, said plate cooperating with the crease plates 46 in positioning the shoe heightwise. As the arms 160 are moved inward by the shoe being positioned in the machine, the teeth 200 on the ratchet plates 198 carried by said arms are moved with relation to the opposing teeth 202 of the pawls 204.

At the beginning of the power cycle of the machine, after actuating the above mentioned treadle (not shown), the rod 274 is moved rearward by powerful spring pressure, the equalizing bar 246 engaging the levers 216 and thus causing the bars 214 to move forward against the action of the springs 218. During the first part of the forward movement of the bars 214 the teeth 202 of the associated pawls 204 move, under the action of the springs 218, into engagement with the teeth 200 of opposing ratchet plates 198, continued forward movement of the bars 214 causing the wedged portions 220 of said bars, backed up by the rolls 222, to bear against the outer end portions of the pawls 204, with the result that the blocks 166 are forced with considerable secondary pressure against the shoe 20. As the shoe is being positioned and initially clamped in the device, the equalizing bar 246 may rock upon the link 248 so that one block 166 may, if necessary, move further inward than the other to equalize pressure against opposite sides of the shoe. After the attachment of the heel to the shoe the machine comes to rest, the rod 274 being moved forward during the last part of the cycle of operation of the machine to release the clamps 56 preparatory to the manual removal of the shoe from the machine.

Having thus described our invention, what we claim as new and desire to secure by Letters Patent of the United States is:

1. In a heel attaching machine, means for positioning a shoe mounted upon a last, said means comprising a centralizing gage movable under pressure of the shoe being positioned, clamps for engaging opposite sides of the counter portion of the shoe, means responsive to movement of said centralizing gage for moving said clamps with equalized primary pressure against the shoe, and power-operated means for moving said clamps with equalized secondary pressure against the shoe.

2. In a heel attaching machine, a device for positioning and clamping a shoe, said device comprising a pair of arms yieldingly movable toward opposite sides of said shoe, crease plates which are supported by said arms and are constructed and arranged to enter the rand crease of the shoe, said crease plates being yieldably mounted for movement with relation to their associated arms about axes disposed heightwise of the shoe, and members which are movable toward and away from each other and have barrel shaped portions respectively, and clamps which have cylindrical recesses for receiving said barrel shaped portions and are adapted to rock upon said barrel shaped portions lengthwise and widthwise of the shoe being positioned.

3. In a heel attaching machine, means for positioning a shoe, clamps movable independently of one another with equalized primary pressure against opposite sides of the shoe in response to movement of said means, and power-operated mechanism for forcing the clamps independently against the shoe with yielding equalized secondary pressure.

4. In a heel attaching machine, a device for positioning and clamping a shoe mounted upon a last, said device comprising a centralizing slide movable in response to lengthwise movement of the shoe being positioned, a pair of arms movable toward and away from opposite sides of the shoe, clamps carried by the arms, an equalizer bar pivoted at its center to the slide, a pair of yieldable connections opposite ends of which are fastened to the arms and to opposite ends respectively of said bar, said clamps operative by said bar, said yieldable connections and said arms being moved with equalized primary pressure against the shoe in response to movement of the slide moved by the shoe, and power-operated means movable with yielding equalizing pressure against the arms for forcing the clamps then in engagement with the shoe with secondary pressure against said shoe.

5. In a heel attaching machine, a pair of arms yieldingly movable toward each other, plates carried by the arms and constructed and arranged to follow in the rand crease of a rearwardly moved shoe, a crease plate constructed and arranged to enter the rand crease at the rear end of the shoe and in cooperation with said crease plates to position the shoe heightwise, clamps pivotally mounted upon said arms respectively for movement toward and away from the opposite sides of the shoe, a bifurcated slide constructed and arranged to be engaged by the rear end of the shoe, mechanism movable in response to movement of the slide actuated by pressure of the shoe for forcing the clamps yieldingly and with equalized primary pressure against opposite sides of the shoe, a back stop for limiting lengthwise movement of the shoe to position the shoe lengthwise, and power-actuated means for forcing the clamps in engagement with the shoe with secondary pressure against opposite sides of the shoe.

6. In a machine for operating upon the heel ends of shoes, a pair of crease plates yieldingly urged toward each other and constructed and arranged to enter the rand crease of a shoe at its opposite sides, a bifurcated slide constructed and arranged to be engaged by the counter portion of the shoe to cooperate with said plates to position the shoe laterally, a pair of clamps constructed and arranged to engage the opposite sides of the counter portion of the shoe in the vicinity of its heel breast line, yieldable operative connections between the bifurcated slide and the clamps for causing said clamps to be forced with primary pressure against the shoe in response to rearward movement of said slide, a back stop for limiting rearward movement of the shoe to position said shoe lengthwise, a yieldable crease plate constructed and arranged to enter the rand crease at the rear end of the shoe as the shoe is moved toward the back stop, and power-operated means for forcing the clamps with yielding secondary pressure against the shoe thus positioned and clamped.

7. In a heel attaching machine, a pair of carriers yieldingly movable equal distances toward and away from a central plane, a pair of crease finders mounted upon the respective carriers, arms pivotally mounted upon carriers, clamps mounted upon the arms respectively, means responsive to movement of a shoe being positioned for moving the clamps yieldingly with equalized initial pressure against opposite sides of the counter portion of the shoe, a ratchet secured to each of said arms, a link pivotally mounted upon

each of the carriers, a pawl pivotally mounted upon each of the links, and power-actuated yieldable means for causing the pawls to move into driving engagement with associated ratchets and then to cause the pawls operating through said ratchets to move the clamps with equalized secondary pressure against the shoe.

8. In a machine for operating upon shoes, means for positioning a shoe which is mounted upon a last lengthwise and widthwise in the machine, a pair of blocks, and mechanism movable in response to lengthwise movement of the shoe being positioned for yieldingly forcing the blocks against opposite sides of the counter portion of the shoe, said mechanism comprising barrel-shaped supports, each of said blocks having a cylindrical passage which has a radius of curvature substantially the same as the maximum radius of curvature of an associated barrel-shaped support so as to enable the block to slide on the barrel, and means for frictionally holding each of the blocks on an associated support, said means being yieldable under pressure exerted by the shoe against the block to enable the block to slide generally lengthwise and circumferentially of the barrel-shaped support as the shoe is positioned in the machine to enable the blocks to orient themselves to the shoe.

9. In a machine for operating upon a shoe mounted upon a last, means for positioning the shoe lengthwise and widthwise, and a pair of clamps constructed and arranged to be forced against opposite sides of the shoe as the shoe is positioned in the machine, each of said clamps comprising a barrel-shaped support, a shoe engaging block having a cylindrical passage which has a radius of curvature substantially the same as the maximum radius of curvature of the barrel-shaped support and in which an associated barrel-shaped support is positioned so as to enable the block to slide on the barrel, and a spring-pressed plate carried by the support and constructed and arranged to hold the block frictionally with relation to the support, said plate being constructed and arranged to yield under pressure of the block to enable said block to slide to a limited extent lengthwise of the barrel-shaped support and also to rock simultaneously therewith generally lengthwise and circumferentially of the support to facilitate orientation of the block to the shoe.

10. In a heel attaching machine, a device for positioning and clamping a shoe mounted upon a last, said device comprising a pair of members yieldingly movable inward toward opposite sides of the shoe, crease plates constructed and arranged to engage in the rand crease of the shoe at its opposite sides, said plates being mounted for pivotal movement upon said members about axes respectively extending generally heightwise of the shoe and arranged adjacent to shoe engaging portions of the plates, a yieldable crease plate constructed and arranged to enter the rand crease at the rear end of the shoe and to cooperate with said first-named crease plates to position the shoe heightwise, a yieldable bifurcated gage cooperating with the first-named crease plates to position the shoe lengthwise, a back gage for positioning the shoe lengthwise, and clamps for holding the positioned shoe against movement.

11. In a heel attaching machine, means comprising a slidable centralizing fork and a pair of crease finder assemblies for positioning a shoe

11

mounted upon a last, a pair of clamping assemblies pivotally mounted on said crease finder assemblies, mechanism for forcing the clamping assemblies against opposite sides of the shoe with yielding equalized primary pressure in response to movement of said centralizing fork, ratchets carried by the clamping assemblies, pawls carried by the crease finder assemblies, yieldable power-actuated mechanism, and means responsive to movement of said power-actuated mechanism for swinging the pawls into operative engagement with associated ratchets and for thereafter moving said ratchets to cause the clamping assem-

12

blyes to be forced with secondary pressure against opposite sides of the shoe.

Certificate of Correction

Patent No. 2,484,074

October 11, 1949

THOMAS BAGGOTT CLARKE ET AL.

It is hereby certified that errors appear in the printed specification of the above numbered patent requiring correction as follows:

Column 2, line 14, for the word "moving" read *movement*; column 8, line 69, after "clamps" insert *yieldingly*;

and that the said Letters Patent should be read with these corrections therein that the same may conform to the record of the case in the Patent Office.

Signed and sealed this 9th day of May, A. D. 1950.

[SEAL]

THOMAS F. MURPHY,
Assistant Commissioner of Patents.
